ABSTRACT

An apparatus comprises a furnace to heat a metal band, rolling mill rolls forming a plurality of tapers at portions of the heated metal band, shearing means to divide the tapered metal band into a plurality of leaf spring units with opposite tapered ends.

APPARATUS FOR MANUFACTURING LEAF SPRINGS HAVING A TAPERED END PORTION

This invention relates to an apparatus for manufacturing leaf springs having tapered end portions.

Leaf springs used in, for example, a vehicle are formed of an elongated metal plate whose end portions are tapered. To manufacture such leaf springs, there is provided an apparatus comprising a shear for cutting a long metal band for every predetermined length to provide plate spring units, a punch for forming a center hole in the plate spring unit, a heater for heating one or both end portions of the plate spring unit, and means for tapering the heated end portion of the plate spring unit.

In such a conventional apparatus, it is required to provide means for transferring individual plate spring units from one step to another and means for fixing the plate spring unit when subject to treatment, causing the apparatus to be bulky and complex in construction. Moreover, leaf springs manufactured with such a conventional apparatus are not uniform in quality.

The object of this invention is to provide an apparatus which is compact and simple in construction and which is capable of producing leaf springs of high quality and high reliability.

The present invention can be more fully understood from the following detailed description when taken in connection with reference to the accompanying drawings, in which:

FIG. 1 is a schematic illustration of method for manufacturing leaf springs using an apparatus in accordance with this invention;

FIGS. 2A to 2C are side and plan views of the leaf springs produced at each step shown in FIG. 1;

FIGS. 3 and 4 are respectively a plan view and a side view of the apparatus in accordance with this invention;

FIG. 5 is a schematic illustration of the method for manufacturing leaf springs using the apparatus shown in FIGS. 3 and 4;

FIG. 6 is a block diagram of a control circuit for controlling a rolling mill roll used in the apparatus shown in FIGS. 3 and 4;

FIG. 7 illustrates the dimensions of a leaf spring manufactured with the apparatus under control of the control circuit;

FIG. 8 shows an enlarged view of part of the leaf spring shown in FIG. 7;

FIGS. 9A to 9D are sectional views of leaf springs produced with the apparatus; and

FIGS. 10A to 10D are perspective views of the leaf springs which can be formed using another apparatus in accordance with this invention.

Referring now more in detail to the drawings, there is schematically illustrated in FIG. 1 method for manufacturing leaf springs using an apparatus in accordance with this invention.

An elongated metal band 10 is heated to a predetermined temperature, for example 900°C, at heating step A. A heating furnace providing a furnace temperature of 900°C may be used for this heat treatment. The metal band 10 heated is transferred to taper forming step B to be pressed and tapered at predetermined intervals in the form as shown in FIG. 2A. A portion 12 is defined by opposite tapered portions 11 to form a leaf spring unit. Then, the metal band 10 is fed to shearing step C to be cut along the broken lines (FIG. 2A)

between adjacent tapered portions so that the leaf spring units 12 are separated from each other (FIG. 2B). If required, the leaf spring unit 12 is reheated and fed to center hole forming step D to be bored with a center hole 13, thereby providing a complete leaf spring unit 12 (FIG. 2C). The center hole forming step D, however, can be eliminated or carried out prior to, for example, the step C.

An apparatus of this invention for manufacturing leaf springs according to the steps mentioned above may be designated to continuously carry out the steps. Therefore, the apparatus may be made compact and simple in construction and is capable of producing leaf springs of high quality and high reliability.

FIGS. 3 and 4 illustrate an apparatus in accordance with this invention and the operation method thereof. The apparatus is provided with a roller table 20 along which a metal band and leaf spring units sheared apart from the metal band are fed. The front portions of this table 20 is so arranged as to introduce a metal band into a heating furnace 21 such as a well known lateral furnace. Furnace temperature of this heating furnace 21 is preferably set at about 900°C so that the metal band may easily be rolled. Disposed following the heating furnace 21 is a taper forming unit 22 which includes a pair of rolling mill rolls 23 and 24, and two pairs of pinch rolls 25 and 26 respectively arranged at the input and output sides of the rolls 23 and 24. Each leaf spring unit may be tapered at both end portions by pressing the leaf spring unit between rolls 23, 24 while the upper roll 23 moves vertically. The leaf spring unit, now tapered, is fed along the roller table to the subsequent step, shearing step C. The step C is carried out by a pair of shearing blades 27 and 28 arranged on the upper and lower sides of the roller table, respectively. The upper blade 27 is hydraulically driven in a vertical direction against the stationary lower blade 28 to cut off the metal band at a portion between the adjacent tapered portions thereby obtaining discrete leaf spring units.

The roller table 20 is divided at a rear portion into two tables 20a. Disposed at the junction is a separating means 29 which selectively feeds the leaf spring units to the tables 20a. The leaf spring units are fed to and reheated by reheating means 30 on the tables 20a. Then, the leaf spring units are fed to assemblies of punches 31 and dies 32 mounted on the tables 20a so as to carry out the center hole forming step D. The punches 31 may be vertically moved to punch the leaf spring unit supported by the dies 32 so that a center hole may be formed at the center of the leaf spring unit.

Referring now to FIGS. 6 to 9 the relationship between the rolling mill rolls and the pinch rolls in the taper forming step is detailed below.

As shown in FIG. 6, a pulse generator 40 is operatively connected to one of the pinch rolls 25 and other pulse generators 41a and 41b are connected to the lower and upper pinch rolls 26 respectively. Each of the pulse generators 40 and 41a produces a pulse signal according to the rotation of the corresponding roll and the pulse generator 41b produces a pulse signal according to the vertical movement of the upper roll 26 or each when the upper roll 26 vertically moves through a predetermined distance. The pulse generators 40, 41a and 41b are connected to the output terminals of a logic circuit 42 which stores the information on the dimensions of a leaf spring to be formed, that is, length l_1 of the front tapered portion 11a of the leaf spring

unit, thickness t_1 at the front end, length l_2 of the rear tapered portion $11b$, thickness t_2 at the rear end, overall length L and thickness T at the center portion (see FIGS. 7 and 8). The output terminal of the logic circuit 42 is connected to a pulse motor 43 so that the motor 43 may be rotated according to the output pulse signal of the logic circuit 42. The motor 43 drives a screw down mechanism 44 which, in turn, drives the upper roll 23 in a vertical direction.

In this embodiment, a pulse signal is generated from the pulse generator 40 each time a predetermined length of the metal band has passed through between the rolls 25 and then the pulse signal is applied to the logic circuit 42 so as to be processed depending on the preset value of the dimensions of the leaf spring stored in the logic circuit 42. An output pulse signal is generated from the circuit 42 corresponding to its input signals and then applied to the motor 43 so that the motor 43 may be driven and vertically move the upper roll 23 to roll the metal band into a predetermined shape. Where, for example, the leaf spring unit is tapered at the front end portion, first the upper roll 23 is set at the height equal to the thickness t_1 at the front end of the leaf spring and then the upper roll 23 is upwardly moved through Δh each time the metal band advances through Δl . The upward movement of the roll 23 may be stopped when the formation of the taper is completed. Likewise, the taper at the rear end portion of this leaf spring unit may be formed after the metal strip moves through a predetermined distance.

The pinch rolls 26 are provided to check that the leaf spring unit is tapered in a desired shape. When the tapered portion formed by the rolling rolls 23 and 24 passes through between the pinch rolls 26, the lower pinch roll 26 rotates so that the pulse generator 41a may produce a pulse signal each time the leaf spring unit advances through a distance Δl . At the same time, the pulse generator 41b may produce a pulse signal each time the upper pinch roll 26 vertically moves through a distance Δl . Both pulse signals generated from the pulse generators 41a and 41b are applied to the logic circuit 42 and compared with the preset values stored therein. If the leaf spring is not tapered in a predetermined form, the output signal from the logic circuit 42 is corrected according to the difference between said both pulse signals and the preset values stored in the circuit 42. The corrected output signal is applied to the pulse motor 43 so as to control the movement of the roll 23 thereby to roll the metal strip in a predetermined form.

With the apparatus mentioned above, it is possible to taper the end portion of the leaf spring in a linear or curved form by suitably choosing the preset values of the dimensions of the leaf spring. The input and output side tapered portions may be formed symmetrically or asymmetrically.

FIGS. 9A to 9D illustrate leaf springs which may be made by the apparatus of this invention. A leaf spring shown in FIG. 9A has end portions $11a$, $11b$ linearly and symmetrically tapered with respect to the crosswise central line, a leaf spring of FIG. 9B has linearly tapered assymmetrical end portions $11a$, $11b$, a leaf spring of FIG. 9C has symmetrical end portions $11a$, $11b$ tapered with the same curvature R and a leaf spring of FIG. 9D has assymmetrical end portions $11a$, $11b$ tapered with different curvatures R_1 and R_2 respectively.

In the embodiment above mentioned, the lower roll 24 is stationary but it is possible to move the lower rolling mill roll in a vertical direction so as to form leaf springs shown in FIGS. 10A to 10D. A leaf spring shown in FIG. 10A has both end portions $11a$, $11b$ linearly and symmetrically tapered with respect to the crosswise central line on both upper and lower sides, a leaf spring of FIG. 10B is similar to that shown in FIG. 10A except that its both end portions $11a$, $11b$ are asymmetrically tapered, a leaf spring of FIG. 10C has both end portions $11a$, $11b$ symmetrically tapered with the same curvature relative to the crosswise central line on both upper and lower sides, and a leaf spring of FIG. 10D is similar to that shown in FIG. 10C except that its both end portions $11a$, $11b$ are asymmetrically tapered.

What we claim is:

1. An apparatus for manufacturing leaf springs having a tapered end portion comprising: heating means to heat a metal band, taper forming means for forming a plurality of tapers at portions of the heated metal band disposed in predetermined intervals, shearing means to divide the tapered metal band into a plurality of leaf spring units having a tapered end, and moving means for moving the metal band to shearing means from the heating means through the taper forming means.

2. An apparatus according to claim 1 which further includes center hole forming means for forming a center hole in each of leaf spring units.

3. An apparatus according to claim 2 which further includes reheating means for reheating the leaf spring unit to be provided with a center hole.

4. An apparatus according to claim 2 wherein the center hole forming means includes a vertically movable punch and a stationary die, the leaf spring units fed between the punch and die.

5. An apparatus according to claim 1 wherein the heating means includes a lateral furnace through which the metal band is moved.

6. An apparatus according to claim 1 wherein the taper forming means includes a pair of rolling mill rolls at least one of which is vertically movable.

7. An apparatus according to claim 6 which further includes control means for automatically moving the rolling mill roll in a vertical direction to form the tapered portion.

8. An apparatus according to claim 7 wherein the control means includes a pair of first pinch rolls between the heating means and rolling mill rolls, a first pulse generator connected to the pinch rolls to produce a pulse signal each time a predetermined length of the metal band is passed between the pinch rolls, a logic circuit storing the information on the dimensions of a leaf spring to be formed and receiving the pulse signal from the first pulse generator, so that the pulse signal is processed depending on the preset value of the dimensions of the leaf spring whereby the logic circuit generates an output pulse corresponding to the pulse signal from the first pulse generator, a pulse motor connected to the logic circuit to be driven by the pulse signal from the logic circuit and a screw down mechanism driven by the pulse motor to vertically move one roll of said rolling mill rolls.

9. An apparatus according to claim 8 which further includes a pair of second pinch rolls disposed between the rolling mill rolls and shearing means, one of the second pinch rolls being vertically movable in contact with the one side of the leaf spring unit where the taper is

formed, a second pulse generator connected to said one second pinch roll to produce a pulse signal each time said one second pinch roll vertically moves through a predetermined distance, and a third pulse generator connected to the other of said second pinch rolls to produce a pulse signal each time a predetermined length of the leaf spring unit is passed between

the second pinch rolls, the second and third pulse generators respectively connected to the logic circuit in which the pulse signals from the second and third pulse generators are set to be processed depending on the 5 preset value of the dimensions to correct the pulse signal from the logic circuit.
